[57] ABSTRACT

A machine for filling upright cartons of generally rectangular cross-section with product after first applying sealing tapes to the lower ends of the cartons and before applying sealing tapes to the upper ends of the cartons. The machine incorporates several new and improved mechanisms for operating on the cartons and is particularly characterized by the novel mounting of certain ones of the mechanisms to enable the machine to be changed over comparatively quickly and easily from running cartons of one size to running cartons of a different size.

CONTINUOUS MOTION PACKAGING MACHINE FOR CARTONS WITH SEALING TAPES

BACKGROUND OF THE INVENTION

This invention relates generally to a packaging machine and, more particularly, to a machine of the type used for packaging a product in cartons of generally rectangular cross-section. With a machine of this type, initially collapsed cartons stored in a magazine are erected by a feed mechanism as an incident to their delivery into holders on a carrier or conveyor and then are advanced in the holders along a racetrack-shaped path, the cartons being advanced in upright positions and preferably at high speeds with continuous and uninterrupted motion as opposed to intermittent or step-by-step motion.

During the advance of the cartons along the first straight run of the racetrack path, a lower sealing unit applies a sealing tape across outwardly folded lower flaps of the cartons to close the lower open ends of the cartons. After a filler has deposited a charge of product into each carton, an upper sealing unit applies a sealing tape across the upper flaps and upper open ends of the cartons as the latter are advanced along the opposite straight run of the path. Both sealing units are driven back and forth alongside the path in timed relation with the movement of the cartons so that the sealing tapes can be applied and sealed to the cartons without interrupting the continuous advance of the cartons.

After the upper sealing tape has been applied, the carton flaps are glued and folded to closed positions over the tapes and across the ends of the cartons. A so-called exit conveyor strips the cartons out of the holders on the main carrier and transfers the cartons from the packaging machine to a remote station where the cartons may be accumulated into groups and packed into shipping boxes.

A packaging machine of this general type is disclosed in Lense, U.S. Pat. No. 3,589,248. A somewhat similar machine also is disclosed in Benzon-Petersen U.S. Pat. No. 2,867,159.

SUMMARY OF THE INVENTION

The general aim of the present invention is to provide a new and improved machine of the above character which, when compared with prior machines of the same general type, may be more quickly and easily converted or changed over at the end of one packaging run to handle cartons of different size (i.e., cartons of a different height, width and breadth) during the next run. A correlated object of the invention is to standardize the machine so that the same basic machine can be set up to handle cartons of widely varying sizes. In large, the foregoing ends are achieved by (1) keeping cartons of all heights centered vertically during their advance on a common horizontal datum line extending along the carton path and (2) keeping cartons of all widths and breadths centered horizontally with respect to a common vertical datum line extending vertically of the path. By keeping cartons of all sizes centered on the common horizontal and vertical datum lines, changing over of the machine to handle cartons of a different size may be effected with a significant reduction in the number and complexity of adjustments necessary to be made to the sealing units, the filler and certain other mechanisms for operating on the cartons

and, in addition, the sealing pressure exerted by the sealing units is always kept centered on the cartons to promote uniform sealing of the sealing tapes.

A further object of the invention is to simplify vertical re-positioning of the sealing units and certain other ones of the carton operating mechanisms when changing the machine over to run cartons of a different height by mounting the sealing units and such operating mechanisms on common upper and lower subframes whose elevations may be changed quickly and easily to accommodate the change in the height of the cartons. Also, the filler preferably is mounted on a separate subframe and may be adjusted vertically in unison with the upper sealing unit. The invention also resides in the provision of novel actuating mechanism for adjusting all of the subframes in unison and for adjusting the upper and lower subframes through equal distances but in opposite directions.

Still another aim of the invention is to construct the carton feed mechanism and the filler as modular units which are capable of being easily replaced with different types of modules and which may be easily adjusted in a horizontal direction to facilitate changing over of the machine to handle cartons of a different width and/or breath.

A further object of the invention is to simplify the machine while increasing its ruggedness by providing a single drive mechanism operable to move both the upper and lower sealing units back and forth along the carton path in timed relation with the advance of the cartons.

Another object is to incorporate into each sealing unit a unique and simplified arrangement which backs the carton flaps during the application of sealing pressure to the flaps to seal the tapes and which, at the same time, is capable of effectively isolating the carton carrier from the sealing pressure.

The invention further aims to provide a new and improved exit conveyor which strips the cartons from the main carrier in a more reliable and trouble-free manner than has been possible heretofore, which effects final folding and gluing of the carton flaps, and which acts immediately after an emergency shut down of the machine to fold any flaps that have been glued but not folded at the time shut down occurs.

These and other objects and advantages of the invention will become more apparent from the following detailed description when taken in conjunction with the accompanying drawings.

BRIEF DESCRIPTION OF THE DRAWINGS

FIG. 1 is a perspective view schematically showing the various operations performed on the cartons by a new and improved machine embodying the novel features of the present invention.

FIG. 2 is a perspective view of an exemplary carton adapted to be handled by the machine.

FIG. 3 is a fragmentary plan view of the machine.

FIG. 4 is a fragmentary front elevation of the machine.

FIG. 5 is a perspective view of part of the machine and particularly showing the adjustable subframes.

FIGS. 6 and 7 are enlarged fragmentary cross-sections taken substantially along the lines 6-6 and 7-7, respectively, of FIG. 5.

FIG. 8 is a perspective view schematically showing the drive train for the machine.

FIG. 9 is a fragmentary plan view of part of the carton carrier and showing one of the carton holders.

FIG. 10 is a cross-section taken substantially along the line 10—10 of FIG. 9.

FIGS. 11 and 12 are views similar to FIGS. 9 and 10, respectively, but showing holders adapted to support a carton of a different height, width, and breadth.

FIGS. 13 and 14 are enlarged fragmentary cross-sections taken substantially along the lines 13—13 and 14—14, respectively, of FIG. 4.

FIG. 15 is a plan view of the drive mechanism for the sealing units, part of the view being broken away and shown in section.

FIG. 16 is a fragmentary cross-section taken substantially along the line 16—16 of FIG. 15.

FIG. 17 is an enlarged fragmentary cross-section taken substantially along the line 17—17 of FIG. 15.

FIG. 18 is an enlarged fragmentary view taken substantially along the line 18—18 of FIG. 3.

FIGS. 19 and 20 are fragmentary cross-sections taken substantially along the lines 19—19 and 20—20, respectively, of FIG. 18.

FIG. 21 is an enlarged fragmentary cross-section taken substantially along the line 21—21 of FIG. 18.

FIG. 22 is a fragmentary plan view primarily showing the exit conveyor.

FIG. 23 is a fragmentary cross-section taken substantially along the line 23—23 of FIG. 22.

FIGS. 24 and 25 are enlarged fragmentary cross-sections taken substantially along the lines 24—24 and 25—25, respectively, of FIG. 22.

GENERAL ORGANIZATION OF THE MACHINE

As shown in the drawings for purposes of illustration, the invention is embodied in a packaging machine 29 for depositing a product into packages such as paper-board cartons 30 of rectangular cross-section as the cartons are advanced along a racetrack-shaped path. An exemplary carton is shown in FIG. 2 and includes upright side and end panels 31 and 33 whose upper and lower ends are integral with hinged side flaps 34 and dust flaps 35. The upper and lower ends of the carton are covered by heat sealable safety shields or sealing tapes 36 which are sealed to the flaps as the carton is advanced along the path by the machine with the flaps folded outwardly or reversely as shown in FIG. 2. The flaps of the filled carton ultimately are folded inwardly across the sealing tapes and the ends of the carton and are glued closed.

The general operation of the machine 29 may be explained best by reference to the schematic illustration of FIG. 1 and with more specific reference to FIGS. 3 and 4. Initially, flattened or collapsed cartons 30 stacked in a magazine 37 (FIG. 3) at the right end of the main frame 40 of the machine are stripped one-by-one from the magazine by a transfer device 41 and are delivered to a feeding wheel 43 which erects the cartons as an incident to delivering the cartons to a power-driven carrier or conveyor 45 operable to advance the cartons around the racetrack path with a continuous and uninterrupted motion. During the initial advance of the cartons along the first straight run of the racetrack, the normally upright flaps 34 and 35 are

folded reversely and plowed to outwardly projecting, horizontal positions preparatory to the sealing tapes 36 being applied to the flaps. Reverse folding of the flaps is effected by upper and lower power driven folding wheels 46 (FIGS. 3 and 4) and by stationary plows (not shown).

With continued advance of the cartons 30 along the initial straight run of the racetrack, the lower sealing tape 36 is stretched over the lower ends of the cartons as shown in FIG. 1, the tape being drawn in a continuous strip from a supply roll 47 and being trained around guide and dancer rollers 49 so as to extend beneath the cartons. The sealing tape then is sealed simultaneously to the lower ends of a group of nine cartons by a lower sealing unit 50 comprising a series of nine heated sealing shoes 51 which apply heat and pressure to the tape to seal the latter across the lower faces of the outwardly folded flaps 34 and 35 and to momentarily link the nine cartons together by the strip of tape. The sealing shoes are advanced along the path in unison with and beneath the cartons and, after all of the shoes have become aligned with the overlying nine cartons, the shoes are shifted upwardly into pressing engagement with the lower ends of the cartons to seal the tape to the flaps. Nine lower cutters 53 move along the path with the sealers and are shifted upwardly to sever the sealing tape between the leading and trailing dust flaps 35 of adjacent cartons of the group immediately after sealing has been effected. The cartons thus are separated from one another and each is left with an individual sealing tape across its lower end. The sealing shoes 51 and the cutters 53 then are retracted downwardly away from the cartons and are returned reversely along the path and against the flow of the cartons in order to be in position to pick up and move along with the next group of nine cartons.

As the cartons 30 approach the turn of the racetrack, the lower dust flaps 35 and the outer lower side flap 34 of each carton are folded inwardly to closed positions across the lower end of the carton and the sealing tape 36 by rotatable flap folders 54 (FIGS. 3 and 4) and a plow (not shown). Thereafter, the cartons move into the turn where a filler 55 deposits a charge of product into each carton, the cartons herein being filled with concentrated liquid orange juice in a semi-frozen state. The filler comprises a power-rotated turret 56 which carries a series of nozzles 57 arranged on the same pitch circle as the turn and disposed above the cartons. Successive nozzles register with successive ones of the cartons as the latter first move into the turn, move with the cartons around the turn to fill the cartons with downwardly flowing streams of orange juice, and then recede away from the cartons as the cartons move out of the turn and proceed along the straightaway.

On the straightaway, the upper sealing tape 36 is stretched in a continuous strip across the upper ends of the cartons 30 after being stripped off of an upper supply roll 58 (FIG. 1) and drawn across an upper set of guide and dancer rollers 59. An upper sealing unit 60 substantially identical to the lower unit 50 and including a set of nine upper sealing shoes 51 and cutters 53 then seals and cuts the tape so as to leave each carton with an individual strip of tape across its upper end. After rotatable flap folders 61 (FIG. 3) and a plow (not shown) fold the upper dust flaps 35 and the outer upper

side flaps 34 across the sealed tops of the cartons, the latter are removed from the main conveyor 45 by an exit conveyor 63 (FIGS. 1 and 22) and are advanced along the exit conveyor where further operations (to be described subsequently) are performed on the cartons.

THE DATUM LINES AND THE CARTON CONVEYOR

In many instances, the same machine 29 may be used for a period of time for filling cartons 30 of one size within a given range of sizes and then may be changed over and adjusted to run and fill cartons of a different size within the range. For example, the machine initially may be set up to run comparatively small cartons 30 (FIGS. 9 and 10) of a given height h , width w , and breadth b . After a certain number of the small cartons 30 have been run, the machine may be changed over to run larger cartons 30' (FIGS. 11 and 12) of a greater height h' , width w' , and breadth b' . As used herein, width refers to the lateral dimension of the cartons between the side panels 31 while breadth refers to the dimension between the end panels 33, the latter panels being disposed in leading and trailing relationship as the cartons are advanced.

In one of its aspects, the present invention contemplates reducing the number and complexity of the adjustments needed to be made to the machine 29 to change the latter over from running cartons 30 of one size to running cartons of a different size. This is achieved by uniquely arranging the main conveyor 45 so that all cartons, regardless of their height h , are kept centered vertically on a common horizontal datum line HL (FIGS. 10 and 12) as the cartons are advanced by the conveyor, the datum line being an imaginary line extending along the path of advance of the cartons. In addition, cartons of all widths and breadths are kept centered horizontally on a common vertical datum line VL (FIGS. 9 and 11) so that, regardless of their width or breadth, all cartons are advanced while being substantially centered with respect to various ones of the carton operating mechanisms such as the sealing shoes 51 and the cutters 53 of the sealing units 50 and 60 and also the nozzles 57 of the filler 55. As will become more apparent subsequently, the use of the common horizontal and vertical datum lines HL and VL simplifies changing over of the machine 29 and enables the machine to be constructed in a simpler but more rugged manner than prior similar machines capable of running cartons of different sizes.

More specifically, the main conveyor 45 advantageously comprises a single chain which is trained around a pair of sprockets 64 and 65 (FIG. 5) to travel in a horizontal plane around the racetrack, the sprocket 64 being power driven to advance the chain 45. Sets of upper and lower holders 66 and 67 (FIGS. 9 and 10) are spaced along and secured to the chain and are adapted to receive the cartons 30 to cause the cartons to advance with the chain. As shown most clearly in FIG. 9, each holder is generally U-shaped and includes a pair of outwardly projecting legs 69 whose inner ends are spanned by a web 70. The legs and web of each holder coact with one another to define a rectangular opening 71 with dimensions approximately equal to the width and breadth of the carton 30 so that each carton fits snugly into the opening with the center

of the carton substantially coinciding with the center of the opening and centered horizontally on the imaginary vertical datum line VL. The datum line VL extends vertically of the opening 71, is spaced laterally from the chain 45 a fixed predetermined distance, and may be considered to be at a fixed predetermined location along the chain. Also, it will be apparent from FIG. 10 that the carton 30 is centered vertically on the imaginary horizontal datum line HL which is disposed in a horizontal plane passing through the center of the chain.

To attach the holders 66 and 67 to the chain 45, three screws 73 (FIGS. 9 and 10) extend through the web 70 of each holder and through a mounting plate 74. The mounting plates of the upper and lower holders are secured to the chain by pins 75 extending through the chain links and are held in rigid, spaced apart relation by tubular spacers 76 which threadably receive the upper and lower attaching screws 73. Further rigidity is added to the holders by guide members 77 which are secured to the inner sides of the mounting plates 74 by screws 79 and which slide along rigid, stationary tracks 80 disposed above and below the chain and extending along the inner sides of the straight runs of the chain, the tracks helping to support the chain.

The holders 66 and 67 are used with the machine 29 when the latter is set up to run the comparatively small cartons 30 shown in FIGS. 9 and 10. When the machine 30 is changed over to run the larger cartons 30', the holders 66 and 67 are detached from the mounting plates 74 and are replaced with holders 66' and 67' (FIGS. 11 and 12). As shown, each of the holders 66', 67' includes legs 69' and a web 70' that define an opening 71' which is larger than the openings 71 of the holders 66, 67 and which is correlated in size with the width w' and the breadth b' of the large carton 30'. The outside peripheral dimensions of the holders 66' and 67' are identical to the outside dimensions of the holders 66 and 67, but the legs 69' and the webs 70' are made narrower than the legs 69 and the webs 70 so as to make the openings 71' larger than the openings 71. As a result, when the holders 66' and 67' are attached to the chain 45 and when one of the large cartons 30' is placed in the holders, the carton is automatically centered vertically with respect to the same vertical datum line VL used in reference to the smaller cartons 30. That is to say, a vertical reference line passing through 35 the center of the opening of one of the large cartons 30' carried by the chain 45 is spaced laterally the same predetermined distance from the chain and is located in the same predetermined position along the chain as a vertical reference line passing through the center of the 40 opening of one of the small cartons 30 when the latter is located at a corresponding position along the racetrack. Where, as in this instance, the sizes of the 45 cartons 30 and 30' fall within a given range of sizes, the horizontal spacing or pitch between adjacent sets of the 50 holders on the chain remains the same regardless of whether the holders 66, 67 or the holders 66', 67' are attached to the chain.

Because the cartons 30, 30' are kept centered on the 55 common vertical datum line VL, the nozzles 57 of the filler 55 automatically register with the openings of the cartons as the latter proceed around the turn of the racetrack and thus the angular spacing between the

nozzles and the radial positioning of the nozzles on the turret 56 do not require adjustment when the machine is changed over to run cartons of a different breadth or width. In other words, the nozzles and liquid streams discharged therefrom can remain in the same physical positions relative to the racetrack regardless of the width or breadth of the cartons being run as long as the carton breadth does not fall outside of a given range of breadths. Also, the sealing shoes 51 of the lower and upper sealing units 50 and 60 are automatically maintained in a centered relationship with respect to both the width and the breadth of the cartons and thus the sealing pressure exerted by the shoes can be kept centered on the cartons without need of adjusting the relative position of the shoes either along the chain 45 or laterally of the chain when the machine 29 is changed over.

While cartons 30, 30' with symmetrical leading and trailing dust flaps 35 have been illustrated and while the openings of such cartons herein are maintained centered on the common vertical datum line VL, it should be realized that the leading and trailing dust flaps of each carton may be dissimilar in shape and that the dust flaps of the small cartons 30 need not necessarily be shaped the same as the dust flaps of the larger cartons 30'. In some instances where the dust flaps of the large and small cartons are not symmetrical, it may be desirable to maintain all cartons centered on a common vertical datum line located midway between the leading edge of the leading dust flap and the trailing edge of the trailing dust flap rather than keeping the cartons centered on a vertical datum line extending through the center of the opening of the carton.

As shown most clearly in FIG. 12, the webs 70' of the holders 66' and 67' are each formed with a vertically extending neck 81. When the holders 66' and 67' are attached to the mounting plates 74 by screws 73' which are longer than the screws 73, the necks 81 cause the vertical spacing between the upper and lower holders 66', and 67' to be greater than the vertical spacing between the holders 66, 67 shown in FIG. 10 by an amount equal to the difference in the height h' of the carton 301 and the height h of the carton 30. Accordingly, when a large carton 301 with a height h' is placed in the holders 66' and 67', such carton is automatically centered vertically on the same horizontal datum line HL as the smaller carton 30. Thus, the use of different holders for the different sized cartons 30 and 30' results in cartons of both sizes being kept centered vertically on the same horizontal datum line HL and also centered horizontally on the same vertical datum line VL as the cartons are advanced around the racetrack by the chain 45.

Adjustments to compensate for the change in height of the cartons are made in reference to the horizontal datum line HL so that the elevation of the chain 45 need not be changed. Thus, when the machine is changed over, for example, from running cartons 30 of one height h to running cartons 30' of a greater height h' , those particular mechanisms such as the lower sealing unit 50 which operate on the bottoms of the cartons are lowered from their former positions through a distance equal to one-half the difference between the height of the cartons 30, 30' while those mechanisms, such as the filler 55 and the upper sealing unit 60,

which operate on the tops of the cartons are raised through an equal distance. If the machine is changed over to run shorter cartons, the lower operating mechanisms are raised and the upper operating mechanisms are lowered. Because of the common horizontal datum line, the elevation of the feeding wheel 43 need not be changed when the machine is changed over to run cartons of a different height. In addition, the loading imposed on the chain by the cartons, by the carton holders, and by the sealing pressure exerted by the sealing units 50 and 60 is always symmetrical about the vertical center of the chain regardless of the height of the cartons. Thus, the chain is not subjected to unequal force moments as would be the case if the holders 66 and 67 were spaced vertically from the chain by different distances.

THE MAIN FRAME AND THE DRIVE FOR THE CARTON CONVEYOR

Now that the basic concept of maintaining the common horizontal and vertical datum lines HL and VL has been explained, it is appropriate to describe certain structural aspects of the machine 29 in more detail. For purposes of explanation, the main frame 40 may be considered as comprising a center section 83 (FIG. 5) and left and right end sections 84 and 85 which all are formed of frame members suitably welded together to form a box-like frame unit, exemplary ones of the frame members being shown in FIGS. 6 and 14 and being indicated by the reference numerals 87 and 88, respectively, in those views. A peaked roof 90 (FIGS. 5 and 13) is attached to and covers the upper side of the center frame section 83 to streamline the frame and to prevent foreign material from fouling various mechanisms housed within the frame beneath the roof.

The conveyor sprocket 64 is mounted on a shaft 90 (FIG. 8) supported by the right end portion of the center frame section 83 and is power-rotated to advance the chain 45. To rotate the sprocket 64, a main drive motor 91 is connected by a belt drive 93 to a shaft 94 which acts through an adjustable, variable speed gear box 95 and an electric clutch 96 to turn a pinion 97 on a shaft 99. The pinion meshes with and turns a bull gear 100 which is secured to the shaft 90 beneath the sprocket 64. Advantageously, the sprocket may be driven selectively at a very slow rate to inch the chain 45 along slowly but continuously for purposes of setting up and checking out the machine 29. Thus, a comparatively small and normally de-energized inching motor 101 (FIG. 8) is connected to the shaft 94 through a gear box 103 and a normally disengaged electric clutch 104. When the inching motor 101 is energized and the clutch 104 engaged, the sprocket 64 is driven at a much slower rate than is the case when the sprocket is being driven by the main motor 91. During inching, the main motor 91 is de-energized and its rotor simply free-wheels as the belt 93 is driven by the shaft 94.

THE CARTON FEED MODULE

When the machine 29 is changed over from running cartons of one width to running cartons of a different width, the carton feeding wheel 43 (FIG. 3) must be adjusted toward or away from the sprocket 64 so that the cartons can be placed properly in the holders 66, 67 on the chain 45 as the holders are driven around the

sprocket. Thus, when the machine is changed over to run cartons of a lesser width, the feeding wheel must be adjusted toward the sprocket by a distance equal to one-half the difference between the width of the wider and narrower cartons. The feeding wheel must be adjusted by a corresponding distance but away from the sprocket when the machine is changed over to run wider cartons.

According to an advantageous aspect of the invention, the feeding wheel 43, the transfer device 41 for delivering the cartons to the wheel, and the magazine 37 for storing the initially flattened cartons all are constructed as a modular unit and all are adapted to be adjusted in unison toward and away from the sprocket 64. By arranging the wheel 43, the transfer device 41 and the magazine 37 as a feed module, the position of the wheel relative to the sprocket 64 can be adjusted as necessary when the machine is changed over to run cartons of a different width and yet a constant relationship is maintained between the wheel, the transfer device and the magazine to avoid the need of adjusting the three relative to one another when the position of the wheel is changed.

As shown in FIG. 3 and FIGS. 5 to 7, the feeding wheel 43, the transfer device 41 and the magazine 37 all are supported on a box-like base 105 which, in turn, is mounted slidably on the upper side of the right end section 85 of the main frame 40 to move toward and away from the center section 83 of the frame and the sprocket 64 supported thereon. Thus, the feeding module is formed by the wheel 43, the transfer device 41, the magazine 37 and the base 105 so that adjustment of the base effects adjustment of the other elements in unison with one another. To mount the base 105 for sliding on the end frame section 85, wear plates 106 (FIG. 7) are fastened to the lower sides of the base and ride along machined pads 107 fastened to the frame members 87. A clamping plate 108 underlies each pad 107 and is fastened to the base by a clamping screw 109 and an adjusting screw 110. When the clamping screw is loosened, the base may be slid horizontally on the pads 107 to position the feeding wheel 43 in the proper location relative to the sprocket 64 to deliver the cartons 30 to the holders 66 and 67. Adjustment of the base is facilitated by two actuator screws 111 (FIG. 6) rotatably mounted in the right end of the base and threaded into a plate 112 which is anchored to the extreme right end frame member 87. After first loosening the clamping screws 109, the actuator screws 111 may be turned to either draw the base toward the sprocket or to force the base away from the sprocket. A cover plate 113 (FIG. 5) fastened to the left end of the base fits slidably over the right end of the peaked roof 90 and closes the gap between the base and the center frame section 83 in all adjusted positions of the base.

It will be apparent that the construction of the feeding wheel 43, the transfer device 41 and the magazine 37 as a modular unit with the base 105 enables the transfer device and the magazine to be adjusted in unison with the feeding wheel when the latter is shifted to a different position to deliver cartons of a different width to the cartons holders. As a result, it is not necessary to adjust the transfer device and the magazine relative to the feeding wheel each time the machine 29 is

changed over to run cartons of a different width. Moreover, the feed module may be replaced quickly and easily with a different module for feeding specially designed cartons of a different type than the cartons 30.

THE LADDER FRAMES

As pointed out above, the mechanisms, such as the upper and lower sealing units 60 and 50, which operate on the upper and lower ends of the cartons 30 are adjusted vertically by equal amounts but in opposite directions when the machine 29 is changed over to run cartons of a different height. In accordance with an important aspect of the present invention, vertical adjustment of the upper and lower operating mechanisms is facilitated greatly by mounting most of the mechanisms which operate on the upper ends of the cartons on a common upper subframe 114 (FIG. 5) and by mounting most of the mechanisms which operate on the lower ends of the cartons on a common lower subframe 115. Both subframes are mounted for vertical adjustment on the main frame 40 and preferably are arranged to be power-adjusted at the same time but in opposite directions. In this way, most of the upper and lower operating mechanisms may be adjusted in unison when the machine is changed over to run cartons of a different height and thus it is not necessary to adjust each of the mechanisms individually.

The upper and lower subframes 114 and 115 are somewhat similar in appearance to ladders and thus will be referred to hereafter as ladder frames. Each of the ladder frames 114, 115 is spaced above the peaked roof 90 on the center frame section 83 and each comprises a pair of elongated bars 116 (FIG. 5) extending lengthwise of the machine 29 and interconnected by a pair of primary cross bars 117. As shown most clearly in FIGS. 5 and 13, four jack screws 119 are connected to the primary cross bars 117 of the ladder frames for the purpose of adjusting the ladder frames vertically. Each jack screw includes a reduced diameter lower end portion 120 (FIG. 13) which is journaled in a bearing unit 121 supported on the roof 90 of the center section 83 of the main frame 40, the screw jack being captivated against endwise movement relative to the roof. Each screw further comprises a right-hand threaded portion 123 threaded into a nut 124 fixed to the primary cross bar 117 of the lower ladder frame 115, an intermediate unthreaded portion 125 rotatably received in bushings 126 which are fixed relative to the main frame 40, and a left-hand threaded portion 127 threaded into a nut 129 fixed to the primary cross bar 117 of the upper ladder frame 114. Thus, when the jack screws are rotated simultaneously, the ladder frames are adjusted in unison relative to the main frame 40 through equal distances but in opposite directions so that one ladder frame may be lowered and the other raised when the machine 29 is changed over to run cartons of a different height.

To rotate all of the jack screws 119 simultaneously, a reversible motor 130 (FIGS. 5 and 13) is supported on the main frame 40 and acts through a gear box 131 to drive a chain 133. The latter is trained around sprockets 134 on a pair of shafts 135, each shaft extending between and driving right angle gear boxes 136 connected to the lower ends 120 of those screws

located on the same side of the ladder frames. Thus, when the motor 130 is energized in one direction, all of the jack screws are rotated in unison to raise one ladder frame (e.g., the upper frame 114) and to lower the other ladder frame. If the motor is energized reversely, the upper frame is lowered while the lower frame is raised. As shown in FIGS. 3 and 4, the lower ladder frame 115 carries the lower sealing unit 50 as well as the lower wheel 46 for unfolding the carton flaps, the lower tape supply roll 47, the lower guide and dancer rollers 49, the lower flap folders 54, various plows and other mechanisms for operating on the bottoms of the cartons. The upper ladder frame 114 carries not only the upper sealing unit 60 but also the upper unfolding wheel 46, the upper tape supply roll 58, the upper guide and dancer rollers 59, the upper flap folders 61, plows and other mechanisms for operating on the tops of the cartons. Accordingly, energization of the motor 130 to adjust the ladder frames changes the elevation of all of these operating mechanisms in unison and in the proper direction to avoid the need of adjusting each of the mechanisms individually when the machine 29 is changed over to run cartons of a different height.

THE FILLING MODULE

The elevation of the filler 55 also must be adjusted when the machine 29 is changed over to run cartons of a different height so that the nozzles 57 will be located at the proper level. While the filler possibly could be mounted on the upper ladder frame 114 and adjusted with the upper sealing unit 60 and the other upper operating mechanisms when the elevation of the upper ladder frame is changed, the weight of the filler normally is such that the upper ladder frame would be adversely unbalanced and, in addition, would require jack screws substantially larger than the jack screws 119. The present invention contemplates mounting the filler on a separate vertically adjustable subframe 137 (FIG. 14) and changing the elevation of such subframe in unison with the upper ladder frame so that the filler 55 may be adjusted at the same time, in the same direction, and through the same distance as the upper sealing unit 60 and the other upper operating mechanisms but without subjecting the upper ladder frame to the weight of the filler.

In general, the vertically adjustable subframe 137 for supporting the filler 55 is disposed adjacent the left end section 84 of the main frame 40. For a purpose which will be explained subsequently, the filler 55 and the vertically adjustable subframe 137 advantageously coact with a supporting base 139 to form a filling module which is adjustable horizontally on the left end frame section 84 in such a manner that the entire filling module can be moved toward and away from the center frame section 83.

More specifically, the supporting base 139 of the filling module comprises a peaked roof section 140 (FIG. 14) overlying the horizontal frame members 88 of the left frame section 84 and fitted slidably at its right end with the left end of the main roof 90 covering the center frame section 83. Rigid with and depending from the ends of the end roof section 140 are upright plates 141 (one shown in FIG. 14) to which are attached elongated horizontal wear plates 143. The latter ride along machined pads 144 fastened to the upper

sides of the horizontal frame members 88 and are adapted to be clamped releasably to the pads by clamping plates 145 underlying the pads and connected to the wear plates by clamping screws 146 and adjusting screws 147 similar to the screws 109 and 110 of the feeding module. Thus, when the clamping screws 146 are loosened, the supporting base 139 formed primarily by the end roof section 140 may be slid along the frame members 88 of the end frame section 84 to shift the base toward or away from the center frame section 83. Suitable actuating screws (not shown) similar to the actuating screws 111 of the feed module may be provided to effect sliding of the base 139 on the frame members 88.

The supporting base 139 further comprises a lower plate 149 (FIG. 14) connected rigidly to arms 150 formed integrally with and depending from the upright plates 141. Anchored to the lower side of the horizontal plate 149 is a gear box 151 which houses a vertically fixed rotatable nut 153 threaded onto an actuating screw 154 extending downwardly into the gear box and projecting upwardly through the lower plate 149. When the nut 153 is rotated in one direction or the other, the screw 154 remains rotationally stationary but threads through the nut so as to translate upwardly or downwardly for purposes of raising or lowering the filler 55 and the subframe 137. An input shaft 155 extending into the gear box 151 effects rotation of the nut 153 and is connected by a splined coupling 156 (FIGS. 4 and 5) to a shaft 157 which is connected by a chain 159 to the gear box 131 driven by the ladder frame adjusting motor 130. Thus, when the motor 130 is energized to adjust the ladder frames 114 and 115 by means of the screw jacks 119, the actuating screw 154 also is shifted either upwardly or downwardly to effect simultaneous vertical adjustment of the filler 55. The splined coupling 156 between the shafts 155 and 157 permits the base 139 and the gear box 151 to be shifted horizontally along the stationary frame members 88 while still maintaining a driving connection between the two shafts.

Anchored rigidly to the upper end of the actuating screw 154 is a lower bushing member 160 (FIG. 14) which is fastened to an upper bushing member 161, the latter in turn being bolted to a horizontal disc 163 forming part of the subframe 137 for the filler 55. Three angularly spaced arms 164 radiate outwardly from the disc 163 and, at their free ends, carry upright rods 165 (FIGS. 4 and 14) whose upper ends are connected to the filler 55 to help support the latter. Two of the rods 165 are located outboard of the left end of the end roof section 140 while the third rod extends upwardly through the right end portion of the end roof section as shown in FIG. 4.

Disposed above and bolted to the disc 163 is a hub 166 (FIG. 14) which is telescoped slidably into a sleeve 167 welded to and extending through the peak of the end roof section 140. An additional hub 169 is rotatably journaled in the upper end portion of the sleeve 167 by bearings 170 and is bolted at its upper end to the idler sprocket 65 of the main conveyor chain 45, the hub 169 being suitably anchored against axial movement within the sleeve 167. The filler 55 is disposed above the idler sprocket 65 and its turret 56 is driven by the sprocket as the latter turns so as to effect

operation of the filler in timed relation with movement of the chain 45 and with the advance of the cartons 30. For this purpose, a vertical shaft 171 (FIG. 14) is fitted into the hubs 166 and 169 and is connected at its upper end to drive the filler. A key 173 fastened to the hub 169 projects into an elongated keyway 174 formed in the shaft 171 and couples the shaft for rotation with the idler sprocket 65 while permitting endwise sliding of the shaft within the hub. The shaft 171 is rotatably received within the hub 166, and the latter is held against rotation relative to the sleeve 167 by a key 175 which is fastened to the sleeve and which projects into an elongated keyway 176 in the hub to permit the hub to slide upwardly and downwardly within the sleeve. At its lower end, the shaft 171 extends rotatably through the disc 163 and is journaled in the upper and lower bushing members 160 and 161, the shaft being supported by a thrust bearing 177 disposed between the bushings.

With the foregoing arrangement, energization of the ladder frame adjusting motor 130 turns the input shaft 155 (FIG. 14) to shift the actuating screw 154 upwardly or downwardly. The bushing members 160 and 161, the disc 163, the arms 149 and the support rods 165 (all of which may be considered to make up the subframe 137) shift vertically with the screw 154 to change the elevation of the filler 55 and to locate the nozzles 57 in the proper vertical position to fill cartons of a given height. The hub 166 and the drive shaft 171 also shift vertically with the screw 154, but the idler sprocket 65 remains stationary by virtue of the sliding fit between the key 173 and the keyway 174. In this way, the drive shaft 171 is adjusted vertically with the filler 55, the idler sprocket 65 remains at a fixed level to keep the main chain 45 at a constant elevation, and a driving connection is maintained between the sprocket and the shaft by the key 173 so that the filler will be operated as the chain is driven. Accordingly, it will be apparent that the filler is vertically adjusted in unison with the ladder frames 114 and 115 and that, when the machine 29 is changed over to run cartons of a different height, the filler is automatically positioned at the proper elevation as an incident to adjusting the upper sealing unit 60 and the other mechanisms for operating on the upper ends of the cartons.

Under certain circumstances when the machine 29 is to be used for running cartons with a significantly different breadth b, b' than the cartons 30 or 30', it is necessary to change the pitch between adjacent pairs of holders 66 and 67 on the chain 45. That is, the horizontal spacing between adjacent pairs of holders must be increased if the machine is to accommodate cartons of a significantly greater breadth and preferably is decreased when the machine is to run cartons of a significantly lesser breadth. When the pitch of the holders is changed, the chain 45 is often lengthened or shortened and, to enable a change in the length of the chain, the idler sprocket 65 must be shifted away from or toward the driving sprocket 64, thus changing the horizontal distance between the sprockets. The construction of the filler 55, the subframe 137 and the supporting base 139 as a modular unit enables the distance between the sprockets 64 and 65 to be changed quickly and easily. That is to say, when the clamping plates 145 (FIG. 14) are loosened, the sup-

porting base 139 may be slid on the frame members 88 of the end frame section 84 and may be shifted toward or away from the center frame section 83. In so shifting, the base 139 moves the vertically adjustable subframe 137, the filler 55 and the idler sprocket 65 in unison toward or away from the center frame section 83 and thereby causes a change in the horizontal distance between the sprockets 64 and 65 without changing the relationship between the filler and the idler sprocket. Thus, by constructing the filler 55 and its supporting structure 137, 139 as a module which is horizontally adjustable on the main frame 40, the filler and the idler sprocket 65 may be easily re-positioned when the length of the chain 45 is to be changed as a result of changing the pitch of the holders 66 and 67. In addition, the filler 55 and its supporting structure 137, 139 may be removed easily from the main frame 40 as a unit or a module and replaced with another module with a different type of filler. The same basic machine 29 thus may be easily modified and used with different fillers for packaging different types of product.

THE DRIVE MECHANISM FOR THE SEALING UNITS

In another of its aspects, the invention contemplates the novel provision of a single drive mechanism 180 (FIG. 8 and FIGS. 15 to 17) operable to move both the lower sealing unit 50 and the upper sealing unit 60 back and forth along the path of the cartons 30 so that the sealing shoes 51 may move along with and seal the cartons as the latter are advanced with continuous motion by the chain 45. By using the single drive mechanism 180 for both sealing units, the machine is simplified since the need for separate drive mechanisms driven from a common power source is avoided and, in addition, the single drive mechanism may be made more rugged and durable while occupying less overall space on the machine 29 than is the case when individual or separate drive mechanisms are used for each sealing unit.

More particularly, the drive mechanism 180 is primarily housed within a box 181 which is anchored rigidly to the center frame section 83 midway between the two straight runs of the chain 45 as shown in FIG. 3. The tracks 80 for supporting the chain 45 are secured to the outer sides of the box (see FIG. 10) and, in addition, the box supports the bushings 126 which receive the screw jacks 119 (see FIG. 13).

Advantageously, power to the drive mechanism 180 is supplied by a pinion 183 (FIG. 8) which meshes with and is driven by the bull gear 100 on the sprocket shaft 90. The pinion acts through a gear box 184 to rotate an output gear 185 which, in turn, meshes with a gear 186 on one end of a shaft 187 journaled on the center frame section 83. The gear 186 and a gear 189 on the other end of the shaft 187 rotate gears 190 located outside of the box 181 and fixed to the outer ends of shafts 191 (FIGS. 15 and 17) journaled in the sides of the box. Sprockets 193 are carried on the inner ends of the shafts 191 and drive endless chains 194 (FIGS. 8 and 16) which are trained around idler sprockets 195 fast on the inner ends of shafts 196 journaled in the sides of the box 181.

Each chain 194 is supported in a very rugged manner and is held against any substantial deflection. Thus, a

center guide 197 (FIG. 16) anchored to the box 181 is disposed between the upper and lower straight runs of each chain 194 and coacts with upper and lower guides 199 disposed above and below the runs to prevent the runs from flexing upwardly or downwardly. Curved guides 200 also extend partially around the sprockets 193 and 195 and prevent the chains from flexing away from the sprockets.

As the chains 194 are driven around the sprockets 193 and 195, their motion is converted into back and forth linear movement for shifting the sealing units 50 and 60 along the path of the cartons 30. For this purpose, a pin 201 (FIG. 17) is connected between the chains 194 and supports a bearing 203 which pivotally mounts one end of an elongated pitman 204 (FIGS. 8, 15 and 16) on the pin. The other end of the pitman 204 is connected pivotally to a member in the form of a car 205 which is guided for back and forth sliding within the box 181, the car carrying rollers 206 which ride along tracks 207 secured to the inner sides of the box. Arms 209 (FIG. 8 and FIGS. 15 and 16) anchored to the car 205 project outwardly through slots 210 in opposite sides of the box and are connected to the sealing units 50 and 60 to move the latter back and forth along the carton path as the car is reciprocated.

Accordingly, assuming that the pin 201 is traveling along the lower straight runs of the chains 194 from right to left as viewed in FIG. 8, the car 205 is shifted to the left to move the lower sealing unit 50 in the direction of the flow of the overlying cartons and at the same speed as the cartons. During this time, the lower sealing shoes 51 are in engagement with the cartons to seal the sealing tape 36 thereto. At the same time, the sealing shoes 51 of the upper sealing unit 60 are disposed in upwardly retracted positions out of engagement with the underlying cartons on the other side of the chain 45 and are being returned idly in a direction opposite to the flow of the cartons so as to be moved into position to pick up the next group of nine cartons. As the pin 201 passes upwardly around the idler sprockets 195, the car 205 (and thus the sealing units) slowly decelerates and then slowly accelerates in the opposite direction, the lower sealing shoes 51 being retracted downwardly out of engagement with the cartons just shortly before deceleration occurs.

With the pin next moving from left to right (FIG. 8) along the upper runs of the chains 194, the car 205 and the sealing units 50 and 60 are moved to the right at a speed equal to that of the cartons, the lower sealing shoes 51 being returned idly to pick up the next group of cartons. During their movement in the direction of flow of the cartons, the upper sealing shoes are shifted downwardly to seal the upper sealing tape 36 and then are retracted upwardly away from the cartons just before the pin 201 moves around the drive sprockets 193 to effect deceleration and reversal of the sealing units. As the pin again moves to the left along the lower runs of the chains 194, the lower sealing shoes are shifted upwardly into engagement with the cartons.

Accordingly, it will be apparent that the single device mechanism 180 is effective to move both of the sealing units 50 and 60 back and forth along the path of the cartons. The drive mechanism is of comparatively simple but rugged construction and occupies otherwise unused space between the straight runs of the main conveyor chain 45.

THE SEALING UNITS

Only the lower heat sealing unit 50 will be described in detail since the upper unit 60 is basically the same as the lower unit. In general, the lower sealing unit comprises a carriage formed by a pair of cars 210 (FIGS. 8 and 18) connected together by upper and lower bars 211 extending between the cars. Rollers 213 (FIG. 19) journaled on each of the cars 210 ride within and alongside channel-like tracks 214 which are secured rigidly to and adjustable vertically with the lower ladder frame 115.

The drive mechanism 180 moves the cars 210 back and forth along the tracks 214 to effect movement of the sealing shoes 51 along the path of the cartons 30. To move the cars, a link 215 (FIGS. 8 and 19) is pivoted at one end to the center of the upper bar 211 and is pivoted at its other end to the outer end of the arm 209 projecting outwardly from the adjacent side of the car 205. Accordingly, as the car 205 is reciprocated back and forth along the tracks 207, the link 215 transmits the motion to the cars 210 to shift the latter back and forth along the tracks 214 and thus move the lower sealing unit 50 and shoes 51 first with and then against the flow of the cartons 30. Importantly, the articulated link 215 permits the cars 210 of the sealing unit 50 to move vertically relative to the drive mechanism 180 on the main frame 40 when the lower ladder frame 115 is adjusted to change the elevation of the sealing shoes 51. Thus, during adjustment of the ladder frame, the link 215 pivots on the arm 209 and the upper bar 211 to enable the cars 210 and the tracks 214 to shift vertically relative to the drive car 205 and the fixed tracks 207. The upper sealing unit 60 similarly includes cars 219 (FIG. 8) which ride in tracks 220 on the upper ladder frame 114 and which are connected to the drive car 205 by an articulated link 221.

As shown most clearly in FIGS. 18 and 19, each car 210 carries an upright sleeve 223 which slidably receives a rod 224. An elongated beam 225 secured rigidly to and spanning the upper ends of the rods 224 supports the sealing shoes 51, the latter being spaced from one another along the upper side of the beam. To shift the sealing shoes upwardly and downwardly into and out of engagement with the cartons 30, a double-acting hydraulic cylinder 226 is anchored to the lower bar 211 and includes an elongated rod 227 extending out of both of its ends and adapted to be reciprocated back and forth in response to the admission of pressure fluid alternatively into opposite ends of the cylinder. The ends of the cylinder rod 227 are connected pivotally to bell cranks 229 (FIG. 18) pivoted on the cars 210 at 230 and coupled by pivoted links 231 to the rods 224 supporting the beam 225. Thus, as the cylinder rod 227 is reciprocated, the bell cranks 229 and the links 231 raise and lower the beam 225 to shift the sealing shoes 51 into and out of engagement with the cartons. Actuation of the cylinder is controlled in timed relation with the movement of the shoes along the carton path so that the shoes are shifted upwardly after attaining the same forward speed as the cartons and then are retracted downwardly just before decelerating and moving reversely along the carton path.

A. Transmitting The Sealing Pressure

During sealing of the lower sealing tape 36 to the lower ends of the cartons 30, the lower flaps 34 and 35 of each carton are disposed in outwardly folded positions and are located in horizontal planes. The lower dust flaps 35 of each carton lie against the lower sides of the legs 69 of the lower holder 67 while the lower inner side flap 34 lies against the lower side of the web 70 (see FIGS. 9, 10 and 21). The sealing tape is stretched across the lower surfaces of the flaps and, as the sealing shoes 51 shift upwardly and apply upward pressure to the flaps during sealing of the tape, the dust flaps 35 and the inner side flap 34 are backed and supported by the legs 69 and the web 70, respectively.

To back the lower outer side flap 34 of each carton 30 as the sealing pressure is applied, the present invention contemplates the provision of a new and simplified pressure transmitting member 233 (FIGS. 19 to 21) which also closes the open outer sides of the U-shaped holders 67 during sealing and, at the same time, supports the outer sides of the holders and absorbs the sealing pressure exerted by the shoes 51 so as to prevent the holders from being cocked upwardly by the pressure and exerting stress on the chain 45.

As shown in FIGS. 20 and 21, the pressure transmitting member 233 comprises an elongated bar located outwardly of and at the same level as the lower holders 67 and of sufficient length to extend alongside nine of the holders. The inner side of the pressure bar 233 is of U-shaped cross-section and is formed with an inwardly opening slot 234 (FIG. 21) defined between an upper leg section 235 and a lower leg section 236.

The pressure bar 233 is mounted for movement with the sealing unit 50 along the path of the cartons 30 and, when the sealing unit is being returned idly against the carton flow, the bar is disposed in an outwardly retracted, inactive position spaced from the holders 67 as shown in FIG. 19. Just after the sealing unit reverses and just before the shoes 51 are moved upwardly, the pressure bar 233 is shifted inwardly to an active position shown in FIG. 21. In this position, the legs 235 and 236 of the bar 233 embrace outwardly projecting lugs 237 (see FIGS. 10 and 21) on the free ends of the legs 69 of the holders 67, the lugs thus being received in the slot 234. As shown in FIG. 21, the lower leg 236 is sandwiched between the lower outer side flaps 34 and the lugs 237 while the upper leg 235 is sandwiched between the lugs and an extremely rigid, L-shaped rail 239 which overlies and engages the upper surface of the pressure bar 233 over its entire length. The rail spans and is supported on the upper ends of a pair of uprights 240 (FIGS. 18 and 21) fastened to and upstanding from the cars 210. The rail 239 and the uprights 240 thus coact with the cars 210 to form the movable carriage of the overall sealing unit 50.

In its active, inwardly shifted position (FIG. 21), the pressure bar 233 closes the open sides of the U-shaped holders 67 and captivates the cartons 30 in the holders during sealing. When the sealing shoes 51 are shifted upwardly, the outer lower side flaps 34 are pressed against the lower leg 236 and thus are backed rigidly by the leg as the shoes exert pressure on the flaps to effect sealing of the tape. Much of the upward pressure applied by the shoes 51 on the holders 67 is absorbed by the upper leg 235 overlying and engaging the lugs 237

and is transmitted through the leg to the rigid rail 239. The upward sealing pressure ultimately is exerted on the uprights 240 and the cars 210 and is substantially balanced by the downward reaction force applied to the cars when the cylinder 226 shifts the sealing bars 51 upwardly into pressing engagement with the cartons. The rail 239, the uprights 240 and the cars 210 thus form a structural arrangement analogous to the frame of a C-clamp and balance the various forces so as to prevent the sealing force from being transmitted to the tracks 214 which support the cars.

Because the pressure bar 233 supports the outer free ends of the holders 67 during sealing, the holders are prevented from being cocked upwardly by the force exerted by the sealing shoes 51 and thus twisting of the chain 45 is avoided. As a result of the pressure bar 233 and the rail 239 moving along the carton path in unison with the holders 67, no sliding friction is created and thus neither the bar nor the holders need be equipped with anti-friction rollers.

In order to enable the pressure bar 233 to shift laterally into and out of engagement with the holders 67 from the inactive position shown in FIG. 19 to the active position shown in FIG. 21, the bar is mounted slidably on the rail 239 by a series of pins 241 (FIGS. 20 and 21) anchored to and spaced along the bar and mounted slidably in bosses 243 spaced along the rail. Inward and outward shifting of the bar is effected by a double-acting cylinder 244 (FIGS. 18 and 20) mounted on the rail 239 and operable to reciprocate a rod 245 extending outwardly from both ends of the cylinder. The ends of the rod 245 are connected to bell crank linkages 246 pivoted on the rail at 247 (FIG. 20) and fastened at their free ends to the bar 233 as indicated at 249. The cylinder 244 shifts the bar 233 inwardly just after the sealing unit 50 begins moving in the direction of and at the same speed as the cartons 30 and then retracts the bar just before the sealing unit decelerates and reverses.

B. Cutting The Sealing Tapes

As mentioned earlier, the sealing shoes 51 seal a comparatively long strip of sealing tape 36 to a group of nine cartons 30 and thus the cartons are momentarily linked together by the tape. Almost immediately after the tape has been sealed, it is severed between the leading and trailing flaps 35 of adjacent ones of the cartons in the groups to separate the cartons and to leave each with an individual tape. The cutters 53 (FIGS. 18 and 21) for severing the tape comprise generally flat blades disposed in upright planes, there being nine cutters in all with eight of the cutters being successively positioned between adjacent ones of the sealing shoes 51 and with the remaining cutter being located downstream of the left or downstream sealing shoe. With this arrangement, the most downstream cutter severs the sealing tape between the first carton of a simultaneously sealed group and the last carton of a preceding group. The remaining eight cutters sever the sealing tape between the individual cartons of the group while leaving the tape on the last carton of the group connected to the supply roll 47. Accordingly, during the time the sealing unit 50 is being shifted reversely through its return stroke, the sealing tape is pulled along with the advancing last carton of a sealed

group and is stretched across the lower ends of the following group of cartons to be sealed.

In this instance, the cutters 53 are attached to the upper ends of vertical rods 250 (FIG. 21) which are slidably mounted in the beam 225. Each rod 250 is pivotally connected at its lower end to a crank 251 rigid with a rock shaft 253 extending along and supported rotatably by the beam 225. The rod 254 of a double acting cylinder 255 carried on the beam is connected pivotally to a crank 256 fast on the rock shaft 253. Thus, when the cylinder is energized to reciprocate the rod 254, the shaft 253 is rocked first in one direction and then the other to shift the cutters vertically between lowered inactive positions (FIG. 18) and raised cutting positions (FIG. 21), the cutters passing through and severing the sealing tape as an incident to bring shifted upwardly to the active positions. Being carried on the beam 225, the cutters move back and forth along the carton path with the sealing shoes 51 and are shifted upwardly to sever the tape just after the latter has been sealed to the cartons by the shoes. The cutters then are retracted before being decelerated and reversed.

C. Correlation With The Datum Lines

With the cutters 53 and the other elements of the overall sealing unit 50 having been described in detail, several advantages resulting from the use of the common horizontal and vertical datum lines HL and VL can be explained more fully. Because cartons of all widths w are kept centered on the same vertical datum line VL, the sealing pressure applied by the shoes 51 is always centered laterally with respect to the cartons to effect uniform sealing. While the shoes themselves are ordinarily replaced with shoes of a slightly different size when the machine 29 is changed over to run cartons of a different width, the shoes are kept centered on their mounting beam 225 and thus the sealing pressure is kept centered with respect to the cartons. There is no need to adjust the lateral position of the beam nor the lateral positions of the shoes on the beam when the machine is changed over to run wider or narrower cartons and, in addition, the cutters 53 and the pressure bar 233 need not be adjusted laterally. As long as the pitch between the pairs of holders 66, 67 is maintained constant, the machine can be changed over to run cartons of a different breadth b without changing the spacing between the cutters 53 and without changing the center-to-center spacing between the sealing shoes. Because the upper and lower sealing units 50 and 60 are always adjusted vertically through equal distances as a result of the common horizontal datum line HL, the articulated drive links 215 and 221 move equally when the sealing units are adjusted and thus both units can be powered by the single drive mechanism 180 on the main frame 40.

THE EXIT CONVEYOR

After the upper sealing tape 36 has been applied to the cartons 30 and the upper dust flaps 35 and the upper outer side flap 34 folded closed by the flap folders 61, the cartons are removed from the holders 66 and 67 by the exit conveyor 63 (FIGS. 22 and 23) which transfers the cartons away from the downstream end of the main machine 29. In another of its aspects,

the invention contemplates the provision of a new and improved exit conveyor 63 which gradually and smoothly takes over control of the cartons from the holders 66, 67 to reduce the likelihood of the cartons being dropped or becoming jammed during their transfer to the exit conveyor.

As shown in FIGS. 8 and 22, the exit conveyor 63 is located near the right hand turn of the chain 45 adjacent the idler sprocket 64 and comprises a pair of vertically spaced chains 260 which are supported on the conveyor frame 261 to run in horizontal planes. Fastened to and projecting outwardly from the chains 260 are sets of pushers or paddles 263 spaced apart the same distance as the center-to-center spacing between adjacent sets of holders 66 and 67 and operable to push the cartons along a path which diverges away from the racetrack. The chains are trained around drive sprockets 264 fastened to a shaft 265 journaled on the frame 261 at the downstream end of the exit conveyor, and are driven at the same speed as the chain 45. For this purpose, a chain 266 (FIG. 8) driven by the shaft 99 acts through a gear box 267 and a shaft 269 to drive a gear box 270 which is operably connected to the shaft 265 by a chain 271.

In order that the cartons 30 may be removed gradually from the holders 66, 67 and brought under the control of the exit conveyor 63 while still being conveyed outwardly away from the downstream end of the machine 29, the chains 260 are guided so as to first move the paddles 263 parallel to the straight run of the chain 45 and then to move the paddles along a path diverging away from the straight run. Thus, at their upstream ends, the chains 260 are trained around nose sprockets 273 (FIGS. 8 and 22) and then extend past guide sprockets 274 arranged such that flights of the chains 260 parallel the chain 45 as the flights pass between the sprockets 273 and 274 and then diverge away from the chain 45 downstream of the sprockets 274.

As each carton 30 in the holders 66 and 67 approaches the nose sprockets 273, the carton is gradually cammed outwardly from the holders by an elongated plow 275 (FIG. 22) fastened to the frame 261. The plow generally parallels the diverging runs of the chains 260, intersects the path of the cartons advanced by the chain 45, and is located vertically so as to project in between the upper and lower holders 66 and 67. The upstream end of the plow is located near the nose sprockets 173 and thus each carton advanced by the holders engages the plow and is cammed outwardly of the holders a short distance upon approaching the sprockets. Shortly after the outward camming is initiated, a paddle 263 moves around the nose sprockets and registers with the trailing end panel 33 of the carton while traveling parallel to the adjacent run of the chain 45. With continued advance, the carton is cammed progressively outwardly by the plow and gradually moves out of the holders and alongside the paddle. In this way, control of the cartons is gradually relinquished by the holders 66, 67 and is gradually assumed by the paddles 263 thereby to insure a smooth transfer to reduce the chances of the cartons being thrown from the holders or being jammed in the paddles and possibly causing a shut down.

The cartons 30 are moved along the diverging flights of chains 260 under the full control of the paddles 263 and are supported during such advance by top and bottom guide rods 276 (FIG. 23) disposed above and below the cartons and by inner and outer guide rods 277 and 279 extending along the side panels 31. The outer guide rods 279 and the top and bottom guide rods 276 extend upstream into the area of the chain 45 and help maintain control over the cartons as they are transferred from the holders 66, 67 to the paddles 263. In addition to supporting the side panels 31, the inner guide rods 277 provided a backing for the still outwardly folded inner upper and lower side flaps 34 of the cartons as the latter are advanced by the paddles.

Advantageously, glue is applied to the outwardly folded inner side flaps 34 as the cartons 30 are advanced along the exit conveyor 63 and then the flaps are folded shut to completely close the ends of the cartons. By gluing the flaps while the cartons are on the exit conveyor rather than in the holders 66 and 67 there is no danger of the holders and the other elements of the main machine 29 becoming fouled or contaminated with the glue and spoiling either the cartons or the product deposited therein.

As shown in FIGS. 22 to 24, the glue is applied to the upper and lower inner side flaps 34 by upper and lower hot melt gluing units 280 and 281 mounted on the frame 261 between the sprockets 264 and 274. Glue dispensed from upper and lower gluing pots 283 and 284 (FIG. 24) is deposited on upper and lower gluing wheels 285 and 286 and is coated on the flaps 34 as the cartons 30 are advanced past the wheels. The gluing wheels 285 and 286 are attached to and rotated by shafts 287 and 288 (FIG. 24), respectively, driven by gear boxes 289 and 290 whose input shafts 291 and 292 are driven by a chain 293 (FIG. 8) connected to a gear box 294 driven by the shaft 269.

After being glued, the upper and lower inner side flaps 34 are folded to closed positions across the ends of the cartons 30 by upper and lower folding plows 295 and 296 (FIG. 23) located downstream of the gluing units 280 and 281. Only the upper plow 295 will be described in detail since the lower plow 296 is identical with the exception that the upper plow is arranged to fold the upper flaps 34 clockwise (FIG. 25) while the lower plow is arranged to fold the lower flaps 34 counterclockwise.

Generally, the upper plow 295 comprises three sections, namely, an upstream horizontal section 297, an intermediate section 299 flaring upwardly and outwardly from the upstream section, and a downstream section 300 inclined downwardly from and disposed in the plane of the intermediate section 299. As each carton advances, the upper inner side flap 34 thereof rides across the upstream section 297 and is lifted upwardly. Upward folding of the flap is continued as the flap passes onto the intermediate section 299 and then, upon riding along the downstream section 300, the flap is folded downwardly across the upper end of the carton. A bar 301 (FIG. 22) holds the flap in its closed position while the glue sets up during subsequent advance of the carton beyond the downstream section 300 of the plow.

In certain instances, a malfunction may cause the machine 29 to shut down and stop the advance of the

cartons 30 along the exit conveyor 63. Under such circumstances, the inner flaps 34 of the cartons disposed alongside the plows 295 and 296 would be coated with glue and yet the plows normally would not be effective to fold the glued flaps as a result of the interruption in the advance of the cartons. To prevent the glue from setting up on the flaps in case the cartons are stopped, the plows 295 and 296 are uniquely shifted across the flaps with a positive lateral motion to slap the glued flaps to closed positions.

Thus, specifically describing the upper plow 295, a horizontal extension 303 (FIG. 22) of the upstream section 297 is fastened to a platform 304 (FIG. 25) which is mounted on the frame 261 by a set of pivoted parallel links 305. The rod 306 of an actuating cylinder 307 mounted on the frame is connected to the platform 304 and is operable upon being extended to pivot the links clockwise (FIG. 25).

In so pivoting, the links swing the platform 304, and thus the plow 295, first upwardly and then downwardly while shifting the platform and the plow outwardly across the cartons to the position shown in phantom in FIG. 25. As a result, those flaps 34 lying alongside the plow 295 are slapped to closed positions by the plow and thus are folded before the glue sets up. By means of a conventional control arrangement, the cylinder 307 is actuated automatically in response to a signal indicating that the advance of the cartons has been interrupted.

We claim as our invention:

1. In a packaging machine for operating on packages which, from run to run, may vary in height within a predetermined range of heights, the combination of, a main frame, a power driven carrier on said main frame for advancing said packages along a predetermined path, said carrier maintaining packages of all heights within said range centered vertically on a common horizontal datum line disposed within and extending along said path, upper and lower subframes mounted on said main frame for up and down adjustment relative to the latter and said datum line, upper and lower operating mechanisms carried on said upper and lower subframes, respectively, for operating on the upper and lower end portions of packages advanced along said path, and means selectively operable to adjust said subframes vertically in unison through equal distances but in opposite directions when the machine is changed over to run packages of a different height thereby to enable simultaneous vertical adjustment of said operating mechanisms to the proper operating elevations relative to the upper and lower end portions of the packages of the succeeding run.

2. A packaging machine as defined in claim 1 in which said means comprise upright screw jacks journaled for rotation on said main frame and captivated against endwise movement relative to said main frame, the upper and lower end portions of each screw jack being formed with opposite hand threads and being threadably connected to the upper and lower subframes, respectively, and a reversible power actuator connected to said screw jacks and selectively operable to rotate the latter to adjust said subframes.

3. A packaging machine as defined in claim 1 in which said operating mechanisms comprise upper and lower sealing units spaced from one another along said

path and operable to seal closed the upper and lower ends of the packages, and further including a filler disposed along said path between said sealing units for depositing a charge of product into each package after the lower end thereof has been sealed and before sealing of the upper end thereof, an additional subframe carrying said filler and mounted on said main frame for up and down adjustment relative to the latter, and means selectively operable to adjust said additional subframe in unison with and in the same direction as said upper subframe when the machine is changed over to run packages of a different height thereby to enable adjustment of said filler to the proper elevation relative to the packages of the succeeding run.

4. A packaging machine as defined in claim 3 in further including means mounting said additional subframe on said main frame for horizontal adjustment to enable selective horizontal movement of said filler on said main frame, said carrier comprising a pair of horizontally spaced sprockets and an endless chain trained around said sprockets, means mounting one of said sprockets on said additional subframe for horizontal adjustment with the latter and toward and away from the other sprocket, and said last-mentioned means leaving said additional subframe and said filler free for vertical adjustment without changing the elevation of said one sprocket.

5. A packaging machine as defined in claim 4 further including an upright drive shaft connected to drive said filler, said shaft being supported rotatably on said additional subframe and being adjustable both vertically and horizontally with said additional subframe, and means coupling said drive shaft and said one sprocket for rotation in unison while leaving said drive shaft free for vertical adjustment relative to said one sprocket.

6. A packaging machine as defined in claim 1 further including a feed module for delivering packages to said carrier, and means mounting said module on one end portion of said main frame for horizontal adjustment toward and away from the corresponding end of said carrier.

7. A packaging machine as defined in claim 3 in which said main frame comprises a center section and two end sections, said upper and lower subframes being supported on the center section, said filler and said additional subframe being supported on one of the end sections, a feed module supported on the other of said end sections for delivering packages to said carrier, and means connecting said module and said additional subframe to said main frame for horizontal adjustment of said module and said filler toward and away from one another.

8. A packaging machine as defined in claim 1 in which said operating mechanisms comprise upper and lower sealing units spaced from one another along said path and operable to seal closed the upper and lower ends of the packages, a drive mechanism mounted on said main frame for moving both of said sealing units back and forth along said path, and means for transmitting power from said drive mechanism to said sealing units while accommodating vertical adjustment of said sealing units relative to said drive mechanism when said subframes are adjusted.

9. A packaging machine as defined in claim 8 in which said path is in the shape of a racetrack with said

sealing units being located on opposite straight runs of the path, said drive mechanism being located between said straight runs and including a reciprocating member movable back and forth on said main frame, said power transmitting means comprising a pair of links each connected pivotally at one end to said reciprocating member, the other ends of said links being connected pivotally to said sealing units.

10. A packaging machine comprising a main frame, a carrier on said frame for advancing a series of packages along a racetrack-shaped path with continuous motion, upper and lower sealing units spaced from one another along said path and located on opposite straight runs of the path for sealing the upper and lower ends of the packages, and a filler located along said path and disposed between said sealing units for depositing a charge of product into each package after the lower end thereof has been sealed and before sealing of the upper end thereof, the improvement in said machine comprising, a drive mechanism comprising a power-reciprocated member guided for back and forth movement on said frame and located between the straight runs of said path, and a pair of links each connected at one end to said power-reciprocated member and each connected at its other end to one of said sealing units and operable to move said sealing units back and forth along the straight sides of said path in response to reciprocation of said member.

11. A packaging machine as defined in claim 10 in which each of said links is pivotally connected to said power-reciprocated member and also is pivotally connected to its respective sealing unit to transmit the back and forth motion of said reciprocated member to the sealing unit while permitting vertical adjustment of the sealing unit relative to the reciprocated member.

12. A packaging machine as defined in claim 10 further including upper and lower subframes mounting said upper and lower sealing units for vertical adjustment on said main frame, power-actuated means selectively operable to adjust said subframes vertically in unison but in opposite directions relative to said main frame, and said links being pivotally coupled between said sealing units and said power-reciprocated member to permit vertical adjustment of said sealing units with said subframes and relative to said main frame and said reciprocated member while still transmitting power from said reciprocated member to said sealing units.

13. A packaging machine as defined in claim 10 in which said carrier comprises a pair of rotatable sprockets and an endless chain trained around said sprockets, one of said sprockets being power-driven to advance said chain, said drive mechanism comprising means connected to and actuated by said driven sprocket and operable to convert the rotary motion of said sprocket into back and forth motion for moving said reciprocated member in timed relation with the advance of said chain.

14. A packaging machine as defined in claim 10 in which each of said sealing units includes a carriage movable back and forth alongside said path and further includes a series of sealing shoes movable upwardly and downwardly on said carriage and into and out of pressing engagement with the packages to seal the latter, said carrier including a series of holders movable along said path for supporting and advancing the

packages, an elongated pressure transmitting member carried on and movable with said carriage, means mounting said pressure transmitting member on said carriage for movement into and out of engagement with said holders, and means for moving said pressure transmitting member into engagement with said holders prior to movement of said sealing shoes into pressing engagement with the packages.
